(57) **CLAIM**

The ornamental design for a vehicle bumper, as shown and described.

DESCRIPTION

FIG. 1 is a top perspective view of a vehicle bumper for a vehicle according to our new design;

FIG. 2 is a bottom perspective view of the vehicle bumper of FIG. 1;

FIG. 3 is a front view of the vehicle bumper of FIG. 1;

FIG. 4 is a left side view of vehicle bumper of FIG. 1;

FIG. 5 is a right side view of vehicle bumper of FIG. 1;

FIG. 6 is a top view of the vehicle bumper of FIG. 1; and,

FIG. 7 is a bottom view of the vehicle bumper of FIG. 1.

The rear of the vehicle bumper is unornamented.

The broken lines immediately adjacent the shaded areas as depicted in the FIGURES, represent the bounds of the claimed design while all other broken lines are directed to environment and are for illustrative purposes only; the broken lines form no part of the claimed design.

1 Claim, 5 Drawing Sheets
